(57) **CLAIM**

The ornamental design for mounting system, as shown and described.

DESCRIPTION

FIG. 1 is a bottom view of a mounting system showing the new design.

FIG. 2 is a top view of the mounting system.

FIG. 3 is a left-side of the mounting system.

FIG. 4 is a right-side view of the mounting system.

FIG. 5 is a front-side view of the mounting system.

FIG. 6 is a back-side view of the mounting system.

FIG. 7 is a bottom, back, left perspective view of the mounting system; and,

FIG. 8 is a top, front, right perspective view of the mounting system.

The broken lines in the drawings illustrate portions of a mounting system which form no part of the claimed design.
